UNITED STATES PATENT OFFICE.

WILLIAM H. SMITH, OF SPRINGFIELD, MASSACHUSETTS.

NECKTIE.

1,140,201.

Specification of Letters Patent. Patented May 18, 1915.

Application filed September 30, 1911. Serial No. 652,173.

To all whom it may concern:

Be it known that I, WILLIAM H. SMITH, a citizen of the United States, residing at Springfield, in the county of Hampden 5 and State of Massachusetts, have invented new and useful Improvements in Neckties, of which the following is a specification.

This invention relates to neckties.

The principal object of this invention is 10 to provide a necktie having means whereby the neck band thereof and the knot may be conveniently held in engagement with the collar in the proper position without the employment of metallic fastening devices or 15 projecting button tabs of any character, and to provide a tie in which the neck band will be smooth around the collar and thereby permit its convenient insertion and withdrawal from turned down collars and to 20 serve a good appearance with standing collars when the coat is removed.

Further objects of this invention will appear as the following specific description is 25 read in connection with the accompanying drawing, which forms a part of this application, and in which:—

Figure 1 is a perspective view of the “four-in-hand” tie. Fig. 2 is a sectional view through a collar showing the tie applied thereto. Fig. 3 is a rear perspective view of a modification showing the invention applied to a bow tie.

Referring more particularly to the drawing, 1 and 2 represent the tying ends of the necktie, and 3 the neck band thereof, 4 the knot and 5 an elastic tape which is attached preferably to the inside of the neck band, as shown. This elastic tape is connected at 35 separate points on the neck band and is in 40 normal position of less linear dimensions

than the band of the tie between the points at which the tape is connected, thus producing a full portion 6 which is taken up when the tie is pulled into position around the collar. When the tie is knotted in the 45 usual manner and pulled into position, the elastic is stretched so that the full portion 6 lies directly against the collar, as shown in Fig. 2. The elastic being under tension constantly, holds the band in firm engagement 55 with the collar and the knot in proper position.

In the modification shown in Fig. 3, the elastic is shown secured to the outside of the tie. This arrangement may be adapted with 65 the tie shown in Fig. 1 if such tie be a reversible one.

Having thus fully described the invention, what I claim as new, is:—

A necktie adapted to be inserted between 68 the inner and outer folds of a collar including a neck band and tying ends, and a broadened elastic band secured at its opposite ends to the outer face of the neck band of the tie and arranged in opposed relation with 75 the inner surface of the inner fold of the collar permitting said band to engage under the collar button for preventing any upward movement of the tie, said elastic band being 70 attached to points of the neck band which are farther apart than the normal length of said elastic band, thereby permitting the tie to be stretched between the folds of the collar.

In testimony whereof I affix my signature 75 in presence of two witnesses.

WILLIAM H. SMITH.
